UNITED STATES PATENT OFFICE.

FRANK E. WILSON, OF LITHOPOLIS, OHIO, ASSIGNOR OF ONE-THIRD TO
J. B. KRAMER, OF LANCASTER, OHIO.

PNEUMATIC RAILWAY-GATE.

SPECIFICATION forming part of Letters Patent No. 766,405, dated August 2, 1904.

Application filed November 18, 1903. Serial No. 181,724. (No model.)

To all whom it may concern:

Be it known that I, FRANK E. WILSON, a citizen of the United States, residing at Lithopolis, in the county of Fairfield and State of Ohio, have invented certain new and useful Improvements in Pneumatic Railway-Gates, of which the following is a specification.

This invention relates to that type of railway-gates normally closing road-crossings and adapted for automatic operation by approaching trains, so as to be thrown across the roadway to shut off the traffic as the train passes.

The gates are pneumatically operated, air-conduits being provided intermediate the tracks and extending some distance from the gates, and operating means for supplying air to the conduit is also provided for the purpose of the invention. The conduits communicate with cylinders adjacent the gates, and pistons within the cylinders are operated, being connected by suitable means with the gates, so as to be actuated to throw the gates closed across the track at the crossing or open.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view showing the application of the invention. Fig. 2 is a top plan view showing the operating connections more clearly. Fig. 3 is a partial sectional view through the operating means for supplying air to the conduit and the cylinder carrying the operating-pistons. Fig. 4 is a broken view showing the manner of connecting the gates for simultaneous operation.

Corresponding and like parts are referred to in the following description and indicated in all the views of the drawings by the same reference characters.

In the drawings the road is designated 1

and the railroad-track 2. Gates 3 span the track 2 at the road-crossing, being suitably mounted upon gate-posts 4 for a pivotal or swinging movement across the track of the road in the operation thereof. The gates 3 are disposed in pairs, as before mentioned, and are adapted for a swinging movement common to the track and the road upon actuation of the operating means. The gates serve as cattle-guards when in their normal position across the track, being of special advantage for this purpose. Situated at a distance from the gates and about intermediate of the track-rails are several operating mechanisms by which the gates are operated. The means aforesaid comprises a plurality of cylinders 5, which are mounted in suitable casings 6 upon either side of the road-crossing, the cylinders being inclined, as shown, and situated adjacent each other. Each cylinder has a piston 7 movable therein, each of the said pistons having a toothed piston-rod 8 extending therefrom. The pistons 7 are actuated by toothed segments 9, which coöperate with the toothed piston-rods 8 in a manner readily comprehended. The segments 9 are pivoted by means of pins 10 between the sides of the casings 6 and are weighted at their lower portions, as shown at 11, so as to normally hold the trip-bars 12, which extend therethrough in an upright or approximately vertical position. The trip-bars 12 may be either integrally or otherwise formed with the segments 9, as found most suitable in the practicable manufacture of the same. A conduit 13 is disposed beneath the cylinders 5 and ports 14 lead from the cylinders to the conduit 13, the air being thus forced from the cylinders by the pistons 7 into the conduit, which latter communicates with a cylinder 15, which carries the piston 16, connected directly with one pair of gates. The piston 16, which operates in the cylinders 15, is provided with a tubular piston-rod 17, which is connected by flexible connections 18 to arms 19, carried by the gates adjacent the pivoted ends thereof. The arms 19 extend laterally from the gates, the outer ends of the respective arms being secured to the connections 18 aforesaid. So that the gates may be

simultaneously operated, the outer ends of the respective arms 19 of one pair of gates are connected to the inner ends of the respective arms of the opposite pair of gates, so that actuation of one of the connections 18 by operation of the piston 16 will effect the synchronous movement of the gates. The connections 18 pass about pulleys 20, mounted in any substantial manner. The sets of cylinders 5 10 are of course situated upon the opposite sides of the respective gates, which they are designed to operate.

It will be seen that operation of the connections 18 by one of the pistons 16 will cause 15 a certain amount of slack in the connections 18 of the oppositely-disposed piston, and in order to take up this slack the piston-rods 17 are made tubular and receive coupling-bars 21. The coupling-bars 21 are provided with 20 slots 22, and a pin 23 passes through the slotted portion of the coupling-bars and the piston-rod of each piston 16, securing the coupling-bars 21 thereto and limiting the movement of the said bars. The coupling-bars 25 25 30 are normally held in the position shown in Fig. 3 by the taut connection 18, but should any slack occur in this connection a light coil-spring 24 is adapted to force the coupling-bar 21 outward, so as to take up the slack.

To permit the gates 3 to resume their normal position across the track after a train has passed, trip-levers 25 are situated adjacent the trip-bars 12 and intermediate the track-35 rails, said trip-levers being located between trip-bars 12 and the gates. After the trip-bars have been operated by the approaching train and the gates thrown into an open position across the roadway the trip-lever 25 is 40 also operated by the train, and this lever is connected by the rod 26 to valve means 27, controlling the air-outlet 28, leading from the cylinder 16. When the trip-levers 25 are actuated, the valve means 27, connected to the respective levers, is likewise operated to permit the air to escape from the conduits 13, and the pressure being removed from the piston 16 the gates will be permitted to close across the track, resuming their normal position.

Specifically describing the operation of the invention, a train approaching from the direction indicated by the arrow in Fig. 1 and provided with any suitable trip-throwing means, such as inclined shoes 29, (shown in Fig. 3,) will operate the trip-bars 12 and the pistons 7 and force air into the conduit 13, thus actuating the connection 18 of one of the gates. The sets of gates are thus simultaneously thrown across the roadway, the slack in 60 the connection 18 of the opposite set of gates being taken up, as before described, by the spring 24, actuating the coupling-bar 21. In order that only one piston 16 may be operated by the passing train, the toothed portions of 65 the segments 9 of each set of bars are formed

so that as the trip-bars are actuated away from the gates the toothed portions of the segments will not engage the toothed piston-rods 8, and thus the pistons 7 will not move.

The valve means 27 is operated as the train 70 passes, being opened to permit the air to escape, and the gates are restored to their normal positions across the track.

Springs 50 are connected to the levers 25 by which the valve means 27 are operated, 75 and these springs return the levers 25 to their normal position after the train has passed and the air has escaped from the cylinder 15.

Having thus described the invention, what is claimed as new is—

1. The combination with gates, of cylinders arranged upon opposite sides of the gates, pistons movable in said cylinders, means for actuating said pistons, connecting means between the pistons and the gates, independent 85 valve means adjacent the cylinders aforesaid, independent actuators disposed upon opposite sides of the gates, and connecting means between the said actuator and the remote valve means.

2. The combination with gates, of cylinders arranged upon opposite sides of said gates, pistons disposed in said cylinders, connecting means between the gates and the pistons, independent trip mechanisms for actuation of 95 the pistons in the cylinders, valves disposed upon the cylinders, independent trip-levers arranged upon opposite sides of the gates, and connecting means between said trip-levers and the valves of the cylinders for actuation 100 of the latter.

3. In a device of the class described, the combination with horizontally-swinging gates arranged in pairs upon opposite sides of a crossing, of arms extended laterally from said gates, cylinders, pistons movable within the cylinders, connecting means between the respective pistons and respective arms of the gates, other connecting means between the arms of the respective gates causing simultaneous operation of the opposite pairs of gates, conduits communicating with the cylinders aforesaid, and means for forcing air through the said conduits to cause actuation of the pistons in the cylinders.

4. In a device of the class described, the combination with gates, of cylinders, pistons disposed within the cylinders, connecting means between the pistons and the gates, conduits communicating with the respective cylinders, cylinders disposed adjacent the conduits and communicating therewith, pistons movable in the last-mentioned cylinders, and trip-bars disposed adjacent the said pistons for actuation thereof to force air through the 120 conduits.

5. In a device of the class described, the combination with gates, of cylinders, pistons disposed within the cylinders, connecting means between the pistons and the gates to ef- 130

feet simultaneous operation of the gates, conduits extending from the cylinders aforesaid, other cylinders disposed adjacent the conduits and leading thereto, pistons arranged in the 5 last-mentioned cylinders and provided with toothed piston-rods, toothed segments for actuation of the last-mentioned pistons, and trip-bars extended from the said segments.

6. In a device of the class described, the 10 combination with gates arranged upon opposite sides of a crossing, of cylinders, pistons arranged in said cylinders, connecting means between the pistons and the gates for simultaneous operation of the gates, conduits extending from the cylinders aforesaid, other cylinders disposed adjacent the conduits and connected with the conduits, pistons movable in the last-mentioned cylinders and provided with toothed piston-rods, toothed segments 15 coöperating with the toothed piston-rods to effect operation of the pistons carried thereby, trip-bars extended from the toothed segments, and weight means for restoring the segments 20 to their normal position after actuation 25 thereof.

7. The combination with gates, of cylinders arranged upon opposite sides of said gates, pistons, means for actuating the pistons, piston-rods extended from said pistons, spring-

actuated coupling-bars carried by the piston-rods, and connecting means between the gates and the spring-actuated coupling-bars.

8. The combination with gates, of cylinders arranged upon opposite sides of said gates, pistons movable in said cylinders and provided with tubular piston-rods, trip mechanisms for actuation of said pistons, spring-actuated coupling-bars movable in the tubular piston-rods, connections between the spring-actuated coupling-bars and the gates, and other 30 connections between the gates for simultaneous operation thereof.

9. In a device of the class described, the combination with gates, of conduits, pistons disposed in cylinders adjacent to said conduits, connecting means between said pistons and the gates, other cylinders adjacent to and communicating with the distant ends of the conduits, pistons located in said cylinders, actuating-segments coöperating with the last-mentioned pistons, and trip-bars for operation of 40 said segments.

In testimony whereof I affix my signature in presence of two witnesses.
